UNITED STATES PATENT OFFICE.

CHARLES ALBERT WETTENGEL, OF ST. LOUIS, MISSOURI.

RETORT-PRESS.

1,112,103.

Specification of Letters Patent. Patented Sept. 29, 1914.

Application filed October 24, 1912. Serial No. 727,566.

To all whom it may concern:

Be it known that I, CHARLES A. WETTENGEL, citizen of the United States, residing at St. Louis, in the State of Missouri, have 5 invented certain new and useful Improvements in Retort-Presses; and I do hereby declare the following to be a full, clear, and exact description of the invention, such as will enable others skilled in the art to which 10 it appertains to make and use the same.

My invention relates to mechanism for mechanically operating the nuts upon bolts used in connection with the cover and matrix of a retort press.

One object of my invention is to lessen the 15 manual labor required in manipulating the machines now in use, and to increase the output of the retort press by largely reducing the time consumed, in tightening and 20 loosening the nuts by hand, which I now accomplish by mechanical means.

A further object is to provide a mechanism which will be strong and durable, and which will be simple in construction and 25 easy of operation.

With these objects in view, my invention consists in a hydraulic pressure actuated mechanism characterized as above mentioned and in certain details of construction 30 and arrangement of parts, all as will be hereinafter fully described and pointed out in the claims.

My invention will be readily understood by reference to the accompanying drawings, 35 forming a part of this application, and in which:—

Figure 1 is a side elevation of my invention. Fig. 2 is an end elevation of the same. Fig. 3 is a horizontal section through the 40 clay cylinder. Figs. 4 and 5 are a top plan and side elevation respectively of one of the nut operating levers. Figs. 6 and 7 are a top plan and a vertical section respectively of one of the lower nuts. Fig. 8 is a side elevation of the lever operating bar. Fig. 9 is a top plan view of one of the top locking nuts. Fig. 10 is a vertical section of the 45 same. Figs. 11, 12 and 13 are detail views of modifications of parts of the machine.

In the drawings 1 is a clay cylinder of the ordinary kind, and is connected to the frame or other stationary supporting portion of the press in any preferred manner, insuring the requisite stability. The clay 50 cylinder 1 is provided with locking bolts 2 and 3.

The matrix 4 which is of the usual kind, is pivoted at one end to the locking bolt 3, and is provided at its opposite end with a hook shaped portion which engages the locking bolt 2, when the matrix is closed. The cover 5 is also of usual construction and is mounted in the same manner as the matrix. The cover is provided with a hook shaped portion similar to the matrix, which 65 engages the locking bolt 2.

The locking bolt 2 is provided at its upper end with a screw threaded portion (not shown) which is engaged by a nut 2^a. Said nut is split as shown in Figs. 9 and 10 and 70 is provided with a bolt *a* and nut *b* by means of which the nut may be clamped upon the bolt 2. This construction allows the nut to be adjusted to take up wear and also prevents the nut from turning. A collar may 75 be used instead of the nut but this would not permit adjustment. The lower end of the locking bolt 2 is screw threaded and is provided with the nut 2^b having a lug 16. This lower nut 2^b has a cone shaped bottom 80 for a purpose which will be hereinafter described. An adjustable collar 2^c is also provided upon the locking bolt 2.

The locking bolt 3 is provided at its upper end with the nut 3^a, similar to the nut 2^a. This nut has the lugs 3^b provided with apertures and a pin 3^c passes through said apertures. The pin 3^c engages a slot in the stationary vertical bar 1^a. The nut 3^a is thus held from turning. At the lower end 90 of said locking bolt 3, another nut 3^d having a lug 16 is provided.

Secured to the clay cylinder 1 in any suitable manner are the hydraulic cylinders 6 and 7. The cylinder 6 being of greater 95 diameter than the cylinder 7. The cylinder 6 is provided with a piston 6^a and the cylinder 7 with a piston 7^a.

A bar 8 having projections 9 and 10 is provided with angular arms 8^a, 8^b and the top ends of these arms are connected by the bar 8^b. It is to be noted that the bar 8^b and the bar 8 in effect form a frame and the rams or pistons of the hydraulic cylinders are connected to the angular arms 8^a, 8^b 105 or the ends of the frame. A second frame 11 with its buffer spring 12 is provided to limit the movement of the piston 6^a in its outward stroke.

Nut levers 13 having apertures 14 and 110 sockets 15 are adapted to operate the lower nuts. The levers 13 are also provided with

screw threaded apertures 17^a, for a purpose hereinafter described. The lower nuts 3^a and 2^b fit in the apertures 14 of the nut levers and their lugs 16 engage the sockets 15 of the same. Screws 17 engaging the apertures 17^a of the nut levers are provided to adjust the lugs 16 in the sockets 15. The levers 13 are provided at their outer ends with square headed bolts 18 as illustrated.

10 When the parts of the mechanism are assembled in operative relation, these square heads 18, occupy a position between the lugs 9, 9 and 10, 10. The heads of these bolts are engaged by the lugs 9 and 10 of the bar 8 when the machine is in operation.

The lugs 10 are a greater distance apart than the lugs 9 to allow the full force of the pistons to strike one lever at a time, it having been found in practice that by striking one lever at a time the full force of the operating means is utilized to start the nuts.

20 Hydralic pressure from an accumulator or other source of supply is continuously admitted to the cylinder 7 at 7^c as indicated in Figs. 1 and 3. The same hydraulic pressure under control of a three-way or equivalent valve (not shown) is admitted to cylinder 6 at 6^c as indicated in the same figures. When it is desired to raise the bolt 2 and the top nuts 2^a, and 2^b to permit the cover and matrix to be opened, the cylinder 6 is connected to the water supply and the pressure overcoming the constant pressure in cylinder 7 causes the ram 7^a to move the bar 8 with ram 6^a, thereby moving the bar 8 and projections 9 and 10 to the left, and consequently the nut levers 13. This movement causes the cone of the nut 2^b to be seated and as the nut can go no farther downward, the bolt 2 will rise and with it the nuts 2^a and 2^b. The nut 3^a at the lower end of the locking bolt 3 will be unscrewed slightly permitting the cover and matrix to be turned thereon to open the clay cylinder. When the cover and matrix have been moved to their closed position, water is exhausted from the port 6^c of the cylinder 6 and the constant pressure in cylinder 7 gives a reverse movement to the pistons, bar frame and nut levers.

25 The reason for employing cylinders of different diameters, is to simplify the water connections of the cylinders and the control of the same, the water being at all times connected to the smaller cylinder. By a connection which will permit the water to flow from said smaller cylinder into the larger, the larger piston will force the smaller piston to its original position. The cutting off of the water supply from the larger cylinder connecting said cylinder with an exhaust, permits the water to flow into the smaller cylinder, and as long as the exhaust from the larger cylinder is permitted, the piston of the smaller cylinder will be moved to

effect the exhaust of the larger cylinder and the movement of the connected parts, as heretofore described.

It is not necessary that the lower end of nut 2^b should be conical as all that is absolutely needed is that the nut when loosened, should quickly seat itself upon a stationary part that would prevent its farther descent and raise the bolt 2. Such a structure is shown in Fig. 13 in which the nut is shown as terminating in a plane surface and having a rigid part immediately beneath it.

Instead of having the nut raise the bolt 2 I have also caused the same to be raised by a weight as shown in Fig. 11. In this construction a lever 2^a pivoted to a firm support has one end connected to the collar 2^a or connected directly to the bolt by means such as is shown in Fig. 12; or in any preferred manner. To the opposite end of the lever 85 is secured the weight 2^c sufficiently heavy to raise the bolt. In place of the weight a strong spring 2^f, shown above the lever, may be employed. The raising of the bolt 2 and its connected parts, it will be readily seen, 90 is for the purpose of enabling the matrix and its cover to be easily returned to closed position beneath the parts that engage them and force them tightly in the position required before the operation of the piston in 95 the clay cylinder.

What I claim and desire to secure by Letters Patent is:—

1. In a retort press, the combination with a clay cylinder, of a matrix and cover pivotally mounted at one end on said clay cylinder, bolts and nuts for bringing said parts closely together during the operation of the press, power actuated mechanism and connecting means to loosen said nuts, and means 100 for raising the bolt to which the free ends of said matrix and cover are secured.

2. In a retort press, the combination with a clay cylinder, of a matrix and cover, bolts provided with nuts for holding said parts together during the operation of the press, levers engaging said nuts, a bar provided with projections engaging said levers, and power actuated mechanism for actuating said bar and projections to move said levers to permit said matrix and cover to be moved from their operative positions.

3. In a retort press, the combination with a clay cylinder, of a matrix and cover, bolts provided with nuts for holding said parts tightly together during the operation of the press, levers engaging said nuts, a bar provided with a series of projections for engaging said levers, one of the series of said projections being a greater distance apart than the other to permit the levers to be struck one at a time, and power actuated mechanism for moving said bar and projections.

4. In a retort press, the combination with a clay cylinder, of a matrix and cover, bolts 130

provided at their upper ends with adjustable collars and at their lower ends with nuts for holding said parts tightly together during the operation of the retort press, 5 power actuated mechanism and connecting means adapted to loosen said nuts to permit the said matrix and cover to be moved from their operative positions.

5. In a retort press, the combination with 10 a clay cylinder, of a matrix and cover, bolts provided with nuts for holding said parts tightly together during the operation of the retort press, lugs provided on said nuts, levers provided with sockets and apertures, 15 screws provided in said levers adjacent to said apertures, said nuts resting in said sockets and said lugs resting in said apertures, the screws being adapted to adjust the lugs in said apertures, and power actuated 20 mechanism for moving said levers.

6. In a retort press, the combination with a clay cylinder, of a matrix and cover, a bolt upon which said matrix and cover are pivoted to said clay cylinder, another bolt upon which the free ends of said matrix and cover 25 are secured, nuts provided upon said bolts for bringing the cover and matrix and clay cylinder closely together during the operation of the press, and a rigid part or support closely beneath the nut on the bolt securing the free ends of said matrix and cover, whereby the loosening of said nut will cause it to engage said rigid part or support and raise said bolt. 30

In testimony whereof I affix my signature 35 in the presence of two witnesses.

CHARLES ALBERT WETTENGEL.
